James G. Blunt, Schenectady, N. Y., assignor to
 American Locomotive Company, New York,
 N. Y., a corporation of New York

Application April 1, 1936, Serial No. 72,042

15 Claims. (Cl. 105—2)

This invention relates to streamline locomotives.

An object of this invention is to provide, in a locomotive, a streamline shroud structure comprising a frame work and a shroud composed of separate plates supported by the frame work and held in place by engaged bands without the aid of other fastening means whereby, by removing or loosening appropriate bands, any desired part 10 of the shroud may be removed or replaced as desired without disturbing the remaining parts of the shroud.

A further object is to provide a frame work for the shroud which is secured with suitable parts 15 of the locomotive by bolts and made in separate parts bolted together so that any frame work part or parts can be removed or replaced by the mere removal or replacement of the appropriate securing bolts.

20 A further object is to provide a streamline shroud structure connected with the boiler of a steam locomotive to rigidly secure the structure against movement transversely relative to the boiler, but permitting the boiler to move longitudinally independently of the shroud structure 25 when expanding or contracting under temperature changes.

A further object is to provide a steam locomotive with running boards secured with the locomotive frame independent of the boiler and a shroud structure secured rigidly to the running boards.

30 A further object is to provide a smoke lifter for a steam locomotive, comprising novel characteristics including an air passage for conveying air 35 which, on leaving the passage, operates to aid in lifting the smoke coming from the smoke stack away from the locomotive. This matter, however, is made the subject of a divisional application, 40 and only such reference will be made thereto herein as is desirable for a clear understanding of the merits of the invention covered herein.

A further object is to provide, in a steam locomotive having a boiler secured to the locomotive frame with the capacity for independent movement due to expansion and contraction produced by temperature changes, a cab rigidly secured with the locomotive frame and flexibly secured with the boiler, thereby permitting free movement 45 due to expansion and contraction of the boiler independently of the cab.

50 A further object is to provide, in a locomotive, a streamline shroud, running boards adjacent the shroud, and a cab having a front wall with lateral extensions adjacent the shroud and running

boards, each of said lateral extensions inclining upwardly from the bottom and outwardly from the inner edge in a rearward direction to most effectively receive the streams of air travelling along the shroud and running board thereto and to most effectively direct said streams of air upwardly and outwardly in a rearward direction where they leave the locomotive with any smoke entrained therewith in a most efficient manner.

5 Further objects are to provide, in a locomotive, a shroud in combination with a sandbox and steps, both of novel characteristics.

10 Other objects of and advantages achieved by this invention will be apparent from the following description when considered in connection 15 with the accompanying drawings which illustrate a preferred embodiment of the invention.

The invention is illustrated in the accompanying drawings in which only sufficient of the parts are shown to afford a clear understanding of the 20 invention and wherein Fig. 1 is a side elevation of the front portion of a locomotive involving the present invention, the wheels thereof being shown in dot and dash lines; Fig. 2 is a plan of a longitudinal half of the portion of the locomotive 25 shown in Fig. 1; Fig. 3 is a view similar to Fig. 1, of the rear portion of the locomotive; Fig. 4 is a view, similar to Fig. 2, of the portion of the locomotive shown in Fig. 3; Fig. 5, at the right, is a front view of the left half of the locomotive, and, 30 at the left, is a section of the right half of the locomotive, on the line V—V of Fig. 1; Fig. 6, at the right, is a section of the left half of the locomotive, on the line VI—VI of Fig. 1, and at the left, is a section of the right half of the locomotive, on the irregular line VI'—VI' of Fig. 3; Fig. 7 is a fragmental section of the right half of the locomotive, on the line VII—VII of Fig. 3. The subsequent views are enlarged. Figs. 8—13 are views of the various types of lateral braces or 35 supports employed for securing the shroud frame with the locomotive boiler, Fig. 8 being a fragmental section, on the line VIII—VIII of Fig. 9, of one of the lateral braces or supports connecting the opposite sides of the shroud frame to the 40 boiler, a sectional portion of the boiler and a portion of a shroud frame work angle iron rib being shown at the connections thereof, Fig. 9 a plan of the support shown in Fig. 8, the angle iron rib being shown in section, Fig. 10 a fragmental elevation of one of the braces or supports of the 45 type employed for connecting the shroud frame to the steam dome of the locomotive, Fig. 11 a plan of the support shown in Fig. 10, a fragmental horizontal section of the steam dome being shown 50

at the connection thereof, Fig. 12 a fragmental elevation of a support of the type employed for connecting a side of the shroud frame to the boiler at the firebox end, showing a portion of the boiler in section, and Fig. 13 a plan of the support shown in Fig. 12; Fig. 14 is a fragmental section, on the line XIV—XIV of Fig. 1, of shroud side upper and lower plate sections and a portion of the shroud frame work, including one of the hand rail columns, and also showing a portion of one of the shroud fastening bands; Fig. 15 is a side view of a fragment of the upper margin of a lower plate section of the shroud, showing the slot which engages the hand rail column shown in Fig. 14; Fig. 16 is a view, similar to Fig. 15, of the lower correspondingly slotted margin of a corresponding upper plate section of the shroud; Fig. 17 is a fragmental section, on the line XVII—XVII of Fig. 1, showing the lower portion 10 of a lower shroud plate section, the running board fragmentally, the angle iron for supporting the running board, a shroud frame work rib fragmentally, and a fastening band fragmentally with its associated parts; Fig. 18 is a front view of the parts shown in Fig. 17, the running board being shown in section and the rib and band being disposed at the vertical margins of adjacent shroud plate sections; Fig. 19 is a section on the line XIX—XIX of Fig. 18; Fig. 20 is a fragmental 20 section of the locomotive, including the sandbox, on the line XX—XX of Fig. 3; Fig. 21 is a section of the sandbox on the line XXI—XXI of Fig. 20; Fig. 22 is a fragmental section of the locomotive, on the line XXII—XXII of Fig. 4, showing the connection of the top of the cab with the top of 30 the shroud; Fig. 23 is a similar section, on the line XXIII—XXIII of Fig. 3, showing the connection of the cab near the bottom with the shroud; Fig. 24 is a fragmental side view of the shroud, showing one of the door openings therein and the door therefor; Fig. 25 is an end view of the parts shown in Fig. 24, the shroud being shown in section; Fig. 26 is a fragmental side view of the shroud, showing a step of one of the 40 four pairs of steps employed, the right half showing the right half of the step in open position, and the left half showing the left half of the step in closed locked position; Fig. 27 is a section on the line XXIX—XXIX of Fig. 26, showing the step in closed locked position, and in dot and dash lines, showing the step in open position; Fig. 28 is a section, on the line XXX—XXX of Fig. 26, the step being removed; and Fig. 29 is a fragmental rear view of the left 50 half of the step, as viewed in Fig. 26.

Referring in detail to the drawings, the locomotive can be conveniently divided, from an aspect of the locomotive covering or shroud, into three main portions, namely, a forward portion, denoted generally by the reference letter A, which extends from the front of the locomotive rearwardly for a comparatively short distance along the locomotive smokebox; an intermediate portion B, which includes the major part of the locomotive, and which extends from the rear end of the portion A rearwardly to the front end of the cab of the locomotive; and a rear portion C, which extends from the rear end of the intermediate portion B rearwardly to the rear end of the locomotive.

The locomotive proper, which is a steam locomotive, indicated generally by the reference letter D, may be, in the main, of any suitable construction, and in the present instance is of a con-

ventional 4-4-2 type. It is shown more or less schematic and, as to its principal features requiring special mention, comprises at its forward portion 1 a smoke box, at its portion 2 to the rear of the portion 1 a fire tube boiler, and at its portion 3 to the rear of the portion 2 a firebox, the rear end part 4 of the firebox extending into the forward portion of the cab, denoted generally by the reference numeral 5, a main frame 6 terminating at the front in a bumper bracket 7, a forward truck 8, driving wheels 9, rear truck 10, cylinders and valve chests 11, cylinder saddle 12 to which the smokebox is rigidly secured in the usual manner, the rear portion of the boiler being supported on the main frame 6, as indicated, by supports 13 in the usual manner to permit the usual free movement of the boiler relative to the main frame longitudinally thereof as the boiler, in service, expands and contracts, a smoke stack 14, a steam dome 15, a blow-off muffler (not shown but disposed at the location indicated by the reference numeral 16), safety valves (not shown but disposed at the location indicated by the reference numeral 17), and a running board 18 disposed at each side of the locomotive. Other parts of the locomotive will be later referred to as occasion arises.

Locomotive intermediate portion

A shroud portion, indicated generally by the reference numeral 19, which comprises the covering for the major part of the locomotive intermediate portion, substantially covers the boiler (including the major portion of the smokebox) about the sides and top thereof for substantially its entire length, and extends downwardly at each side to slightly below the top of the driving wheels, a relatively small portion of the smokebox at the forward end being covered by another shroud portion and the smoke lifter, later to be described, and the comparatively small rear end part 4 being within the cab 5. The locomotive is left exposed at the bottom, that is to say there is no shroud portion under the locomotive.

A relatively large angle iron 20, running longitudinally of the locomotive from approximately the point a at the front end of the locomotive rearwardly to the cab 5, is disposed at each side of the locomotive. The side running boards 18 are superposed upon and bolted to the horizontal outwardly projecting legs of the angle irons 20, and are further secured by brackets 21, which it is not necessary here to further describe, except to say that they are each rigidly connected with the running boards by means of bolts, and with the locomotive main frame, thereby firmly securing the running boards, which may be in one or more sections, and the angle irons 20 with the locomotive main frame.

A relatively light frame work, denoted generally by the reference numeral 22, is provided for the shroud portion 19. This frame work comprises a solid bar rib 23 disposed at the front end of the shroud portion 19 and angle iron ribs 24, 25, 26, 27, 28, 29, 30, 31, 32 and 33. The ribs are equally spaced or substantially so with the exception of the ribs 32 and 33, which are more closely spaced than the others. The ribs, at their ends, are offset inwardly and secured to the two angle irons 20 by means of brackets 34 (one being shown enlarged in Figs. 17 and 18), the legs of which are bolted one to the rib and the other to the adjacent angle iron 20, the angle irons 20 being cut away, including a portion of the running boards, and arched angle iron sections 35 inserted in the

cut-away parts to provide open spaces 36 for a purpose later to be mentioned, the rib 26 being shortened and connected to these angle iron sections 35.

5 With the exception of the ribs 24 and 29, the ribs extend from the angle irons 20 entirely around the shroud portion 19 on the inner side thereof. The rib 24 is not continued around the upper part of the shroud portion 19 on account 10 of the smoke stack and smoke lifter (later to be referred to) being located in its path. This rib 24 is made in two parts, the upper ends of the parts being bolted to the outer ends of shroud supports 37 which supports are secured at their inner ends 15 to the smoke stack. Likewise the rib 29 is made in two parts, the upper ends of the parts being bolted to cross ribs 38 which extend between the ribs 28 and 30, to which the cross ribs are bolted, thereby providing a space at the top between the 20 ribs 28 and 30 for the insertion and removal of a sandbox (later to be referred to).

The ribs 23 to 33 are partially curved although they obviously can be given any shape depending upon the shape of the shroud. They are preferably disposed respectively in vertical transverse planes, and, for convenience of description, will be termed vertical ribs. They are connected one with the other by short channel iron ribs 39 running horizontally and interposed between adjacent vertical ribs and bolted thereto by means of angle iron brackets 40, a pair of such brackets being shown in Fig. 14. A horizontal row of these channel iron ribs 39 is provided at each side of the locomotive at the inner side of the shroud portion 19 in the same horizontal plane. A third horizontal row of similar channel iron ribs 41, similarly secured, is disposed at the top and inner side of the shroud portion 19 along the longitudinal center line thereof. The rear 40 most ribs 39 and 41 are bolted at their rear ends to the front wall of the cab 5 and at this end of the cab is secured an angle iron 42, best shown in Figs. 22 and 23. This angle iron takes the irregular shape of the front of the cab, as shown 45 in Fig. 3. The angle iron 42 has a relatively narrow spacer plate 43 welded thereto, upon which is welded a wider plate 44 extending beyond the plate 43 to provide a space between the plate 44 and the adjacent leg of the angle iron 42 for receiving the rear edge margins of the rear 50 plates (later to be referred to) of the shroud portion 19. Similarly the webs of the horizontal row of channel iron ribs 41 have welded thereto a relatively narrow spacer plate 45 upon which is welded a wider plate 46 extending beyond the plate 45 at each side thereof to provide spaces 55 between the plate 46 and the webs of the channel iron ribs 41 for receiving marginal edges of the shroud portion 19 (later to be described).

60 The channel iron rib 41 between the vertical ribs 23 and 24 extends only from the rib 23 to the smoke stack 14 to which it is secured, and the channel iron rib 41 between the vertical ribs 24 and 25 extends only from the rim 25 forwardly 65 to the rear end of the smoke lifter, and is connected at this end with the boiler by a bracket 47. There is little or no movement (due to expansion) of the boiler at this forward end, and therefore these two short ribs 41 may well be secured with 70 the boiler without interfering with the free movement (due to expansion) of the boiler relative to the shroud portion, as will later be further referred to.

There is no channel iron rib similar to the ribs 75 41 between the vertical ribs 27 and 28, but in-

stead thereof there is a metal ring 48 which is connected at diametrically opposed transverse sides to the respective adjacent ribs 27 and 28, short sections of channel iron ribs being disposed, if found necessary, between the ring and the ribs 5 27 and 28. The ring 48 is directly above the steam dome 15 and is not covered by the shroud portion 19 which is cut away at the circumference of the ring, but is covered by a removable cover plate, indicated at 49. A similar, but relatively small, metal ring 50 is provided between the vertical ribs 30 and 31, and another but larger metal ring 51 is provided between the vertical ribs 31 and 32, each connected to its adjacent vertical ribs by short pieces of channel iron ribs, that is to say the adjacent ribs 41 15 are cut away to provide space for the rings 50 and 51.

Both these rings 50 and 51 are left open, that is to say the shroud portion 19 is cut away at 20 these rings. The rings are each provided with a collar 52 which extends downwardly from the ring to the top of the boiler. Within the collar 52 of the smaller ring is the blow-off muffler of the locomotive, and within the collar 52 of the 25 larger ring are the safety valves of the locomotive, neither of these parts of the locomotive being shown in the drawings.

The frame work 22, comprised of the horizontal and vertical ribs, as above described, is supported by the boiler in the following manner: The ribs 25 and 30 are supported by the boiler by brace or support devices, one of which is shown in Figs. 8 and 9. The device comprises a bracket 53 at each side of the adjacent rib. The 35 brackets are welded to the rib, one being fragmentally shown in Figs. 8 and 9, but better shown in Fig. 5, and is of angular formation. The vertical legs of the brackets 53 are orificed to receive rods 54 which are secured to the brackets by pairs of nuts 55 which provide for adjustment of the device. Each of the rods 54, at its inner end, is provided with the plate 56 which is welded to the rod. The plates are welded one to the bottom of its rod, and the other to the top of its rod so 45 that their inner ends may overlap, as shown. The plates 56 are secured on a post 57 which is bolted to the top of the boiler. To this end the plates at their adjacent ends are provided with elongated orifices 58, and the post 57 has an enlarged base 59 and an elongated head 60. In assembling the parts the elongated head is passed through the elongated slots, an end of the head overlapping the end of the upper plate to hold the plates upon the post when the device is finally 55 secured in place. This construction, while holding the shroud portion rigid against movement transversely relative to the boiler, provides a flexible connection with the boiler so that any expansion or contraction of the boiler that may 60 occur, due to changes in temperature, will not injuriously affect the frame work or shroud portion 19, the connections bending slightly during such boiler expansion or contraction.

The ribs 27 and 28 are supported by the boiler 65 in somewhat a similar manner as that just described. Here two devices (best shown in Figs. 10 and 11) are employed at the opposite sides of the steam dome, and for each of the devices a post 61, similar in function to the post 57, is secured by welding to a bracket 62, which is rigidly secured to the adjacent side of the steam dome, the lower plate 56 resting upon the horizontal leg of the bracket 62.

The rib 33 is supported by the boiler in a some- 75

what similar manner as that just described except here each of the plates 56 has its own post 63, and its own bracket 64, the two brackets being rigidly secured to the top of the boiler in spaced relation in order to leave the space above the central portion of the boiler free for boiler fixtures (not shown).

The frame work for the shroud portion 19, as will be noted from the foregoing description, is rigidly supported by the locomotive frame through the angle irons 20 and the running boards 18 which are rigidly connected with the locomotive frame. The frame work is further supported by the boiler at various points of connection but here the connections are flexible, permitting the slight expansion and contraction of the boiler, that may occur due to temperature changes, independently of the frame work, that is to say without harmfully disturbing the frame work.

Hand rails (not shown) are secured one on each side of the locomotive to the two rows of channel iron ribs 39 by columns 65, one being shown of a conventional type in Fig. 14, although any suitable type desired may be employed. In the present instance each side of the locomotive is provided with eight of these columns, substantially equally spaced. Each column is provided with a reduced throat which seats upon the adjacent channel iron rib 39 to provide a space around the throat between the channel iron rib and the enlarged base of the column, the column being bolted to the web of the rib and the space being of sufficient width to admit overlapping edges of plate sections of the shroud portion 19, as will presently appear. The hand rail on each side thus described extends from the cab to the rib 23.

The shroud portion 19, which is made of relatively thin sheet metal, engages the frame work 22 at the outside thereof and extends around the top and down the sides of the boiler to the angle irons 20, where the lower marginal edges are turned outwardly as shown in Figs. 17 and 18. The shroud partakes of the curvature of the frame work, comprising accordingly outwardly slightly curved sides and top with sweeping curves at the upper corners connecting the sides with the top, the sides converging somewhat to meet the sweeping curves. The frame work and shroud portion 19 are spaced from the boiler to provide ample space at the sides and top between the frame work and boiler for the various attachments usually employed in locomotives.

The shroud portion 19 is divided longitudinally to provide transverse strips 66. Each of the strips is divided into four separate sheets or plates. The lower plates on the side of the locomotive shown in Figs. 1 and 3, denoted respectively by reference numerals 67, 68, 69, 70, 71, 72, 73, 74, 75, 76 and 77, extend from the angle iron 20 on this side of the locomotive (where their lower edges are turned outwardly) upwardly to substantially the top of the row of channel iron ribs 39 on this side of the locomotive, and their upper margins are slightly flattened wedge-shape. Those plates disposed at the various locations of the columns 65 are cut out, in their upper margins, to form open slots 78, one being shown in Fig. 15, to permit the margins about the slots to be slipped into the space between the adjacent channel iron rib and the enlarged base of the adjacent column 65.

Plates similar to the plates 67 to 77, and

similarly disposed, are provided on the opposite side of the locomotive.

The upper plates shown in Figs. 1 and 3, denoted respectively by the reference numerals, 79, 80, 81, 82, 83, 84, 85, 86, 87, 88 and 89, have their upper edges disposed at the row of channel iron ribs 41, these edges being tucked in the adjacent space at the side of the longitudinal center line of the ribs 41 provided between the webs of the channel iron ribs 41 and the plate 46. The plates extend from these edges downwardly about the adjacent top and side portions of the frame work 22 to approximately the lower edge of the row of ribs 39 with their lower margins, which are slightly offset outwardly, overlapping the upper wedge-shaped margins of the lower plates so that each upper plate and its adjacent lower plate will make a substantially flush joint at the outer faces thereof. The lower margins of the upper plates, which are located where there is a column 65, are provided with a downwardly open slot 90, one of which is shown in Fig. 16, for engaging the adjacent column within the space there provided, in a manner similar to the engagement by the adjacent lower plate already referred to.

Plates similar to the plates 79 to 89, and similarly disposed, are provided on the opposite side of the locomotive.

The plate 67 overlaps the rib 23 and extends rearwardly to substantially the middle of the rib 24. Each of the successive plates 68 to 76, extends from approximately the center line of its forward adjacent vertical rib rearwardly to substantially the center line of its rear adjacent vertical rib. The plate 77 extends from substantially the center line of its forward vertical rib rearwardly to the cab, its rear edge being shaped to conform to the configuration of the front wall of the cab, and is tucked in the space between the angle iron 42 and the plate 44 already referred to.

The plates of the corresponding row of plates on the opposite side of the locomotive are similarly disposed.

The upper plate 79 extends from substantially the middle of the rib 23 rearwardly to substantially the middle of the rib 24. Each of the successive plates 80 to 88 extends from approximately the center line of its forward adjacent vertical rib rearwardly to substantially the center line of its rear adjacent vertical rib. The plate 89 extends from substantially the center line of its forward vertical rib rearwardly to the cab, its edge being shaped to conform to the configuration of the front wall of the cab, and is tucked in the space between the angle iron 42 and the plate 44 already referred to.

The plates of the corresponding row of plates on the opposite side of the locomotive are similarly disposed.

The plate 79 extends over the smoke lifter to form top and side outer walls about a part thereof, and rests upon the adjacent support 37. It is cut away to meet the rear edge of the support 37 and the adjacent portion of the smoke stack which portion extends from the rear edge of the support 37 to substantially the middle of the front of the smoke stack. The corresponding upper plate at the opposite side of the locomotive is similarly cut away.

The plate 68 is provided with a door 91 which opens to expose the valve gear of the locomotive and any other locomotive part located opposite the door, and is provided at its top with hinges,

and near its bottom edge with latches, as shown. A similar door, but preferably smaller, is provided in the shroud portion at the opposite side of the locomotive for a similar purpose.

5 The plate 80 is provided with a door 92, hinged at the top and provided with a latch at the bottom, as shown, which opens to expose the throttle rod connection of the locomotive. This plate 86 is cut away at its upper forward portion to fit about the rear wall of the smoke lifter and the corresponding plate at the opposite side of the locomotive is similarly cut away.

10 The plates 68 and 70 are cut away at their adjacent lower portions to fit upon the arched angle iron section 35, and a door 93, hinged at the bottom and provided with latches at the top, as shown, is provided to enclose the space 36 and for exposing, when open, the valve gear link of the locomotive. A similar door is provided in the shroud portion at the opposite side of the locomotive for a similar purpose.

15 The plate 81 is provided with a door 94, hinged at the top and provided with a latch at the bottom, as shown, for exposing, when open, wash-out plugs of the locomotive. A similar, but preferably smaller door, is provided in the shroud portion at the opposite side of the locomotive for a similar purpose.

20 The plate 82 is provided with a door 95, hinged at the top and provided with latches at the bottom, as shown, for exposing, when open, one of the check valves of the locomotive. A similar door is provided in the shroud portion at the opposite side of the locomotive for a similar purpose.

25 There is also a door at the opposite side of the locomotive in the plate opposite the plate 83, corresponding to the door 92 in the shroud portion, for exposing, when open, one of the wash-out plugs of the locomotive.

30 The plates 84 and 85 are each provided with a door 96, hinged at the top and provided with latches at the bottom, as shown, for exposing, when open, the sand traps of the locomotive. Similar doors are provided in the shroud portion at the opposite side of the locomotive for a similar purpose.

35 The plates 74, 75, 86, 88 and 89 are each provided with a door 97, the door in the plate 89 being somewhat larger than the other doors of this group, each of the doors being hinged at the top and provided with a latch at the bottom, as shown, for exposing, when open, wash-out plugs of the locomotive. Doors similar to those in the plates 74, 75, 88 and 89 are provided in the shroud portion on the opposite side of the locomotive for a similar purpose.

40 There is also a door at the opposite side of the locomotive in the plate opposite the plate 87 similar to the smaller of the doors 97, and for a similar purpose.

45 The plate 85 is provided with a door 98 disposed near the longitudinal center line at the top of the shroud portion, hinged at the top and provided with a latch at the bottom, as shown, for exposing, when open, a sand filling hole of the sandbox of the locomotive (later to be described). A similar door is provided in the shroud portion at the opposite side of the longitudinal center line for a similar purpose, and a similar door is provided on said opposite side of the longitudinal center line in the plate opposite the plate 80, for exposing, when open, a steam valve of the locomotive disposed at this location.

50 It will be understood that the doors on one side

only are shown in the drawings, and the parts of the locomotive exposed by the doors, when open, in the various instances, are not shown, but are parts of a conventional locomotive, and such parts form no part of the present invention.

5 The plates 84, 86 and 89 near the longitudinal center line at the top of the shroud portion are provided louvers 99, and other louvers are provided opposite these louvers on the opposite side of the longitudinal center line, the louvers 10 serving as exits for the emission of the streams of air passing rearwardly between the locomotive and shroud portion 19, thereby preventing the air between the boiler and shroud from becoming too hot.

10 Folding steps, preferably arranged in pairs, are disposed at various parts of the shroud portion 19 for enabling the attendant to conveniently reach various parts of the locomotive located at the top thereof. These pairs of steps may be on 20 either side of the locomotive, as requirement will indicate. In the present instance the steps, indicated generally by the reference numeral 100, are arranged in pairs, one of the pairs being in the plate 73, and another pair in the plate 75. 25 The pair of steps in the plate 73 is arranged with the upper step of the pair disposed somewhat to the rear of the lower step, and the pair of steps in the plate 75 is arranged with the steps in the opposite order. The pair of steps in the plate 73 30 enables the attendant to reach the sandbox (later to be described) for the purpose of filling same, and the pair of steps in the plate 75 enables the attendant to reach the safety valves and blow-off muffler (not shown) exposed through the open 35 collars 52.

35 Beneath each step the frame work is reinforced by a horizontal angle iron rib 101 bolted to the vertical ribs at the sides of the respective plates 73 and 75. The step is best seen in Figs. 26 to 40 40. The shroud portion 19 is provided with a rectangular opening 102, having an upper edge 103, a lower edge 104, and side edges 105 into which the step fits when closed, forming, at its outer face, a flush joint with the outer face of 45 the shroud portion 19.

45 A latch 106 is provided for securing the step in closed position and comprises a latch pin 107 extending through an orifice in the shroud portion 19 centrally located beneath the lower edge 104, 50 to the inner end of which pin is secured a latch member 108, and at the outer end of which pin is formed a handle 109 for turning the latch from a horizontal inactive position to a vertical up-standing active position. The shroud portion 19 55 is reinforced about the opening 102 at the top thereof by a top horizontal angle iron 110 having its vertical leg welded to the inner face of the shroud portion 19 and its horizontal leg directed inwardly from the upper edge 103 of the opening, 60 at the sides thereof by vertical side angle irons 111, each having one leg thereof welded to the inner face of the shroud portion 19 and the other leg thereof directed inwardly from the adjacent side edge 105 of the opening, the side angle irons 65 111 extending from the top of the top angle iron, to which they are welded, to the top of the cross rib 101, and at the bottom thereof by a bottom horizontal angle iron 112, having its vertical leg welded to the inner face of the shroud portion 19, 70 and its horizontal leg disposed on the lower edge of the vertical leg and directed inwardly, the angle iron 112 being disposed between the lower portions of the angle irons 111 and welded thereto, and the vertical leg of the angle iron 112 be- 75

ing cut away at its central portion to permit the latch member 108 to turn to latching and unlatching positions. The shroud is made of thin sheet material and, except for bands, (later to be described), is unsecured. Therefore it is not well adapted to support the weight that will be carried on the steps. For this reason, while the step frame is secured directly to the shroud, it is nevertheless largely supported by the frame work through the rib support 101 which is part of this frame work and upon which the step frame rests.

Describing the step, for convenience, when in its open position, as shown at the right in Fig. 26, and in dot and dash lines in Fig. 27, it comprises a plate 113, the upper surface of which serves as a tread surface. This plate is of the same size as the opening 102 so that in its closed position it will completely close the opening and make a flush joint with the shroud portion 19. The plate has a reinforcing flange 114 upon the tread surface at the outer edge of the plate and similar side flanges 115, similarly disposed along the side edges of the plate, extending from the flange 114 to substantially the plane of the shroud portion 19 where the flanges are increased in height and thickened inwardly from there on to the inner edge of the plate where they, at their inner ends, slant upwardly inwardly to provide an upper face 30 116 of increased length. The parts of the side flanges 115 of said increased height and thickness are provided with orifices which receive a shaft 117 which also passes through aligned orifices in the inwardly directed legs of the angle irons 111. The plate 113 is thus pivotally connected for swinging to operative position, as shown at the right in Fig. 26, and in dot and dash lines in Fig. 27, and for swinging to closed position, as shown at the left in Fig. 26, and in section in Fig. 27.

40 A plate 118 is disposed within each of the angles of the angle irons 111 and is welded to the inwardly directed legs of the respective angle irons 111, the plate 118 being provided with orifices to permit the shaft 117 to extend therethrough. The plates 118 extend inwardly from the angle irons and on these extended portions are welded stop lugs 119 directed toward the opening 102 and disposed so that their bottom faces will be engaged by the upper faces 116 when the step is 50 swung to open position.

The operation of the step is simple. Usually when unlatched it will drop to open position of its own weight, but it can be assisted to do so, if found necessary, by pressing the portion of the plate 113 below the shaft inwardly. When not in use, the latch being in horizontal position, the step is swung upwardly to closed position, the handle 109 being then turned to bring the latch member 108 to vertical position in engagement with the then inner face of the plate 113 at the lower edge thereof. The latch member has a slightly inclined engaging face, as shown at 120, Fig. 28, to produce the required pressure to hold the step firmly closed, a plate 121 being welded to the angle iron 110 within the opening 102 to serve as a stop for the then upper flange 114.

A sandbox 122 of novel construction, shown best in Figs. 6 and 20, forms a part of the present invention. It is interposed between the top of the boiler and the top of the shroud portion. It 70 comprises a cylindrically curved bottom wall 123 having the curvature of the top of the boiler, a top wall 124, shaped to conform to the shape of the top of the shroud portion 19, side walls 125, and end walls 126. The box is secured above the

boiler by brackets 127 which are secured to the boiler and to the end walls 126. The box is provided with sand feed pipes 128, one being shown in Fig. 20, which lead to the sand traps and are provided with the usual control valves (not shown), the sand trap control valves being disposed opposite the doors 96, as already mentioned.

The box is provided with two filling openings opposite the doors 98, having collars 129, and the shroud portions around these doors are provided with collars 130 which extend into the collars 129, the collars 130 being smaller than the collars 129 to provide a substantial space between a collar 129 and its adjacent collar 130 in order that the sandbox may move with the boiler when the latter expands or contracts, without disturbing the shroud portion. The collars 130 extend for a short distance above the face of the shroud, and the doors 98 extend at all edges beyond the collars 130, and the edges of the doors are turned downwardly, as shown in Fig. 21, to provide leak-proof doors over the filling openings.

The adjacent margins of the transverse strips 66 into which the shroud portion 19 is divided are covered on their exteriors by thin straps or bands 131 which hold the strips 66 firmly in place against the vertical ribs which are disposed immediately opposite the respective bands and which neatly cover the joints between the strips. The bands are provided at their ends with reinforcing plates 132 which are welded thereto, and upon which are welded bolts 133 which extend through orifices in the running boards and the horizontal legs of the angle irons 20, with the exception of the bolts of the band at the angle iron sections 35 which bolts extend through orifices in these angle iron sections 35. The bolts have draw nuts 134 at their threaded lower ends and lock nuts 135. By this means the bands are drawn tightly to hold the plates comprising the strips 66 securely in place. The various bands, with the exception of the second band from the forward end of the locomotive, extend entirely around the shroud portion 19, the plate 46 being cut out to permit the bands to pass. The second band from the forward end is made in two parts and the upper end of each part is provided with a bolting structure comprising the plate 132 and securing bolt 133. Lugs 136 project upwardly from the shroud supports 37, the shroud portion 19 being cut away to permit the lugs to extend therethrough, and these lugs are orificed to receive the bolts 133, nuts similar to the nuts 134 and 135 being applied to the threaded ends of the bolts 133 to anchor the said two parts of this strip at their respective upper ends.

The shroud (streamline covering) of the locomotive comprises another portion, denoted generally by the reference numeral 137. This portion extends from the outer edge of the adjacent running board 18 downwardly to about the top of the driving axles of the locomotive, and for substantially the length of the shroud portion 19. It is bolted to supports 138 which are in line with, or continuations of, the supports or brackets 21, which support the running board. It is not deemed necessary to describe the various supports or brackets which vary in detail, as their specific structures form no part of the present invention, and as a matter of fact any conveniently disposed and designed supports or brackets may be employed. The shroud portion 137 is made in separate strips of relatively thin sheet or plate metal, and the adjacent ends of adja- 75

cent plates or strips are disposed at a support and bolted thereto. A shroud portion, similar to the shroud portion 137, and similarly secured, is provided on the opposite side of the locomotive.

It will be further understood that the shroud portions 19 and 137 may be further reinforced by strips, angle irons or the like welded to their inner surfaces, at various desired locations, to provide additional stiffening means where such means are desired, it being borne in mind that the shroud portions are made of relatively thin sheet material, and are unsupported over relatively large areas. Without further reference it will also be understood that, when desired, similar reinforcements will in practice be made at other portions of the shroud of the locomotive later to be described. It will further be understood that the shroud portions 19 and 137, and the entire frame work 22, are made of separate parts, so secured, as has been previously described, that any or all parts of the shroud portions and frame work parts may be easily removed and replaced. In other words, no welding, rivets or like permanent fastenings are employed that would prevent the disassembling of any or all of the parts comprising the shroud portions and frame work thus far described.

Locomotive rear portion

The cab 5, which constitutes the main part of the locomotive rear portion, is in the main of conventional design, but has the novel feature of being rigidly secured to the frame of the locomotive and flexibly secured to the locomotive boiler in order that the boiler may expand and contract longitudinally independently of the cab. Only those parts of the cab necessary for a clear understanding of the present invention will be described.

The top wall 139 of the cab is in the same plane with the top of the shroud portion 19. The top wall of the cab, at the sides along the lines b (see Figs. 5 to 7), is laterally extended and curved until the side extensions meet the adjacent side walls 140 of the cab, thereby providing a cab of greater width than the part of the locomotive forward thereof, with front walls 141 at each side of the shroud 19. The cab is of a width equal to the distance between the shroud portions 137, and the side walls 140 extend downwardly so that the bottom edges thereof are in line with the bottom edges of the shroud portions 137, thereby making, in effect, a continuation of these shroud portions. The cab maintains the streamline effect of the locomotive shroud or covering.

The locomotive frame is provided with side brackets 142 on which the cab is supported, the cab being rigidly secured to the locomotive frame in any desired manner, as by bolts, welding or the like. The side walls 140 at their lower front edges abut the rear edges of the shroud portions 137 and have welded upon their inner faces plates 143 which overlap the inner faces of the shroud portions 137 to which they are bolted, thereby firmly securing the cab at the front end with the locomotive frame structure.

The front walls 141 of the cab have their inner edges 144 adjacent the rear edges of the shroud portion 19, they being shaped to conform to the shape of the shroud portion at these adjacent edges. The walls 141 recede from these edges rearwardly and outwardly where they meet the walls 140. They likewise recede from their lower edges rearwardly and upwardly where they meet the extensions of the top wall 139, the bottom

portions being somewhat curved forwardly to meet with and merge into their adjacent running boards 18. This double inclination of the front walls 141 enables the streams of air that move rearwardly relative to the advancing locomotive 5 adjacent to the sides of the shroud portion 19 and running boards 18 and any smoke that may be moving therewith to emerge from the sides of the shroud portion 19 and running boards 18 to the walls 141 in a smooth flow on each side of 10 the locomotive. When these streams reach the walls 141, they are directed in outward and upward paths thereby, with the least air resistance, moving outwardly from and above the cab to most effectively and expeditiously cause the air 15 and any smoke present to leave the cab and also the cars to the rear.

The front walls 141 are provided with doors 145 which partake of the same shape as the walls 141, that is to say they recede from their inner 20 edges rearwardly and outwardly, and from their lower edges rearwardly and upwardly, or in other words they are substantially in the same plane with their respective walls 141. The doors are hinged at their outer edges, as shown in Figs. 25 3 and 7 (Figs. 5 and 6, for convenience, not showing the doors), and the doors are secured, when closed, by a latch or otherwise in any usual manner (not shown).

The boiler projects into the cab through the 30 front wall thereof but is left free from this wall in a manner to permit the boiler to expand and contract in a longitudinal direction independently of the cab. As before remarked, the cab, which is rigidly secured to the frame work of the locomotive, is flexibly secured to the boiler to permit the said expansion and contraction but securing the cab rigidly against transverse movement relative to the boiler. This is accomplished in the present instance by a pair of flexible connections 40 146. The connections are disposed at the front of the cab, one at each side of the longitudinal center line but spaced at some distance therefrom and within the space between the top of the cab and the rear portion 4 of the firebox of 45 the boiler. These connections are secured to the front wall of the cab and to the top of the boiler as best seen in Fig. 7. For a detailed description of these connections reference is made to Patent No. 2,155,926, granted to applicant April 25, 1939, 50 which patent is a continuation in part of the present application.

Locomotive forward portion

The locomotive forward portion comprises a 55 front end shroud portion and a smoke lifter.

The front end shroud portion, indicated generally by the reference numeral 154, encloses the front end of the locomotive, and extends from the rib 23 which is disposed at a short distance to the rear of the front of the smoke box forwardly to a point c at the bottom of this shroud portion sufficiently forward of the forward end 155 of the locomotive to provide sufficient space for the coupling of the locomotive (not shown). This shroud portion 154, at its extreme front (forward center line d), is inclined upwardly and rearwardly from its foremost point c at the extreme bottom to the point e at its extreme top, the angle of inclination of this center line being sufficient to permit the shroud portion 154, on each side thereof, to be curved from the center line d rearwardly by suitable horizontally disposed lines of curvature to permit the upper and lower parts, into 70 75

which this shroud portion 154 can be conveniently divided, to meet, at their rear ends, the forward ends adjacent thereto of the shroud portions 19 and 137 respectively making flush joints therewith, to provide maximum efficiency in streamlining of this portion 154 with the portions 19 and 137.

The upper part of the shroud portion 154 comprises a pair of doors 156 which doors are hinged to the respective sides of the rib 23 by hinges 157, and which meet at their front edges at the center line *d* where they are provided with aligned orificed lugs 158 which engage bolts for holding the doors in closed position. The doors can be opened when necessary, by first removing the bolts, thereby exposing the front door of the smokebox, which may be opened, as in ordinary practice, when occasion requires. Each door 156 in practice will preferably comprise a hand rail section (not shown) which will, in effect, be a continuation of the hand rails on the sides of the shroud portion 19 already referred to.

The lower part of the shroud portion 154, that is to say the part below the doors 156, is secured to the front end of the locomotive frame by brackets or framing of any desired construction (not shown). This lower part of the shroud portion 154 comprises a running board 159, which is, in effect, a continuation of the running boards 18. It extends from the forward ends of these boards 18 to the front of the locomotive but gradually decreases in width from the rear ends to the front, as shown in Fig. 2. It is adjacent the bottom edges of the doors 156. This lower part of the shroud portion 154, at its rear edges, is adjacent the forward edges of the shroud portions 137, making flush joints therewith, and extends at these edges from the running board 159 downwardly to the lower edges of the shroud portions 137. This lower portion extends forwardly and is curved inwardly from these edges on each side to the center line *d*, providing effective streamlining in conjunction with the shroud portions 137. Its upper edge follows the running board 159, but gradually recedes from the outer edge of the running board inwardly, to a point indicated at *f*, Fig. 1. The front of this lower part of the shroud portion 154 follows the line *d* from the point *f* to the point *c*. The bottom edge extends from the point *c* rearwardly in horizontally curved lines to oppositely disposed points *g* about in line with the front of the bumper support or bracket 7, and the edges between the points *g* and the bottom of the rear edges of this lower part are formed as sweeping curves disposed in advance of the forward wheels of the locomotive forward truck, as shown in Fig. 1.

This lower part of the shroud portion 154 is provided with four doors, namely the door 160 disposed at the front and near the top of this lower part and forward of a bell 161 of the locomotive, the door having an opening provided with slats 162 (see Fig. 5) to better transmit the sound of the bell to the exterior; the door 163 disposed below and considerably larger than the door 160; and two side doors 164 on opposite sides of this lower part. The doors are hinged and suitably bolted, and, when open, afford access to the various parts of the locomotive located in their vicinity. In Fig. 2 one of the doors 156 and one of the doors 164 are shown in dot and dash lines, partly open.

The various doors in the shroud or covering of the locomotive generally speaking are flush at

their respective outer faces with the outer face of the shroud or covering and shaped similarly thereto at places where located to maintain the streamline effect.

The smoke lifter, denoted generally by the reference numeral 165, is preferably constructed as a separate feature, and then assembled with the locomotive. It extends from a point *h* somewhat to the rear of the smoke stack 14 forwardly to the rib 23, this portion of the lifter being within the shroud portion 19, and forwardly therefrom to the point *e*. The shroud portion constituting the top, front and sides of the smoke lifter, forward of the rib 23, is shaped to somewhat resemble a section of a dome, the rear edge being secured to the rib 23 and curved to form a flush joint with the adjacent part of the shroud portion 19 to maintain the streamline effect therebetween, and the bottom edge being curved to form a flush joint with the doors 156 to maintain the streamline effect therebetween. The shroud forming the exterior of the smoke lifter is provided with front and rear slatted openings 173 for the passage of air into the lifter at the front, and out of the lifter at the rear. Between the front slatted openings provision is made for a horn and a head lamp. Further description of the smoke lifter is not deemed necessary in the present application as this forms the subject matter of a divisional application.

While the invention has been illustrated in the foregoing description in a streamline locomotive of preferred construction, it will be understood that many and various changes and modifications in form, arrangement of parts and details of construction thereof may be made, and that all such changes and modifications as fall within the scope of the appended claims are contemplated as a part of this invention.

The invention claimed and desired to be secured by Letters Patent is:

1. In a locomotive having a main frame, a streamline shroud forming an outer covering for the sides and top thereof comprised of separate plates having adjacent edges disposed in planes transverse of said locomotive; a framework, engaging said shroud upon its inner face, having ribs disposed in said transverse planes and supporting said plates at said adjacent edges; bands disposed in said transverse planes and engaging the outer faces of said plates at said adjacent edges; and adjustable means for drawing said bands tightly upon said plates whereby said plates will be securely held in position upon said framework, said framework and bands, with their adjustable means, being supported by said main frame.

2. In a locomotive having a main frame, a streamline shroud forming an outer covering for the sides and top thereof comprised of separate plates having adjacent edges disposed in planes transverse of said locomotive and other adjacent edges extending longitudinally of said locomotive; a framework, engaging said shroud upon its inner face, having curved ribs disposed in said transverse planes and supporting said plates at said adjacent edges in said transverse planes and ribs extending longitudinally of said locomotive connecting said curved ribs and supporting said plates at said adjacent longitudinally extending edges; bands engaging the outer faces of said plates at said adjacent edges in said transverse planes; and adjustable means for drawing said bands tightly upon said plates whereby said plates will be securely held in position upon said frame.

work, said framework and bands, with their adjustable means, being supported by said main frame.

3. In a locomotive having a main frame and a boiler rigidly secured at one of its ends to said main frame and slidably supported by said main frame beyond said secured end to permit said boiler to expand and contract in a longitudinal direction independently of said main frame, a shroud structure forming an outer covering for the sides and top of said boiler; means rigidly securing said shroud structure at its opposite lower edges to said main frame; and supporting means connected to transversely opposite parts 10 of said shroud structure and to the top of said boiler, thereby preventing either side of said shroud structure from moving laterally outward relative to said boiler.

4. In a locomotive having a main frame and a boiler rigidly secured at its forward end to said main frame and slidably supported by said main frame rearwardly of said end to permit said boiler to expand and contract in a longitudinal direction independently of said main frame, a shroud 20 structure forming an outer covering for the sides and top of said boiler; means rigidly securing said shroud structure at its opposite lower edges to said main frame and to said forward end of said boiler; and supporting means, disposed to the rear of said forward end, connected to transversely opposite parts of said shroud structure and to the top of said boiler, thereby preventing either side of said shroud structure from moving laterally outward relative to said boiler.

35 5. In a locomotive, a main frame; a running board rigidly secured to said main frame at each side thereof; and a boiler disposed between said running boards rigidly secured at one of its ends to said main frame and slidably supported by said main frame beyond said secured end to permit said boiler to expand and contract in a longitudinal direction independently of said main frame and said running boards; and a streamline shroud structure forming an outer covering for 40 the sides and top of said boiler rigidly secured at its lower side edges to said running boards.

45 6. In a locomotive having a main frame, a streamline shroud forming an outer covering for the sides and top thereof having an opening formed therein; a framework engaging said shroud upon its inner face supported by said main frame; a frame secured to said shroud about the edges of said opening; and a foldable step pivotally mounted in the sides of said frame, said framework including a member disposed beneath and adjacent to the bottom of said frame for supporting said frame.

50 7. In a locomotive having a main frame, a streamline shroud forming an outer covering for the sides and top thereof comprised of separate plates having adjacent edges disposed in planes transverse of said locomotive, one of said plates having an opening formed therein; a framework, engaging said shroud upon its inner face, having 55 ribs disposed in said transverse planes and supporting said plates at said adjacent edges; bands engaging the outer faces of said plates at said adjacent edges; adjustable means for drawing said bands tightly upon said plates whereby said plates will be securely held in position upon said framework, said framework and bands, with their adjustable means, being supported by said main frame; a frame secured to said shroud about the edges of said opening; and a foldable step pivotally mounted in the sides of said frame, said

framework having a longitudinally directed rib secured to said ribs disposed in transverse planes adjacent thereto and disposed beneath and in supporting engagement with said frame whereby said shroud is substantially relieved of the weight 5 imposed upon said step.

8. In a locomotive having a main frame and a boiler rigidly secured at one of its ends to said main frame and slidably supported by said main frame beyond said secured end to permit said boiler to expand and contract in a longitudinal direction independently of said main frame, a streamline shroud structure forming an outer covering for the sides and top of said boiler having an opening formed therein and rigidly secured 10 at its lower side edges to said main frame; a sandbox rigidly secured to said boiler opposite said opening having a filling opening formed therein; and a collar secured to said shroud structure about said opening formed therein and extending into, and spaced at its forward and rear ends from the adjacent margins of, said opening formed in said sandbox whereby said sandbox may move with said boiler longitudinally of said locomotive independently of said collar and 15 shroud structure.

9. In a locomotive having a boiler, a main frame and a running board at each side thereof, a streamline shroud structure forming an outer covering for the sides and top of said boiler and 20 extending at its lower side edges to said running board adjacent thereto, said running boards and shroud structure being supported by said main frame; and a cab having its front wall adjacent the rear edge of said shroud structure and comprising a laterally extending portion at each side 25 of said shroud structure having its inner edge engaging the side of said shroud structure adjacent thereto and its bottom edge engaging the rear edge of the adjacent running board, each of said 30 cab front wall portions being inclined from its bottom edge upwardly and from its inner edge outwardly in rearward directions.

10. In a locomotive having a main frame and a boiler rigidly secured at one of its ends to said main frame and slidably supported by said main frame beyond said secured end to permit said boiler to expand and contract in a longitudinal direction independently of said main frame, a shroud structure forming an outer covering for 40 the sides and top of said boiler; means rigidly securing said shroud structure at its opposite lower edges to said main frame; and supporting means at each side of said shroud structure having its outer end secured to the adjacent side of 45 said shroud structure and its inner end pivotally connected with said boiler, the two said supporting means holding said shroud structure against lateral outward movement relative to said boiler.

11. In a locomotive having a main frame and a boiler rigidly secured at one of its ends to said main frame and slidably supported by said main frame beyond said secured end to permit said boiler to expand and contract in a longitudinal direction independently of said main frame, a shroud structure forming an outer covering for 50 the sides and top of said boiler having an opening formed therein and rigidly secured at its lower side edges to said main frame; a sandbox rigidly secured to said boiler opposite said opening having a filling opening formed therein; an open collar secured to said shroud structure about said opening formed therein and extending into, and spaced at its forward and rear ends from the adjacent margins of, said opening formed in said 55

- sandbox whereby said sandbox may move with said boiler longitudinally of said locomotive independently of said collar and shroud structure, said collar extending above said shroud structure; and 5 a cover closing said collar and having a turned down marginal flange extending below the top of said collar exteriorly thereof when in closed position substantially preventing rain and other foreign matter from entering said sandbox.
- 10 12. In a locomotive, a main frame structure; a cab rigidly secured to said frame structure at the rear end portion thereof; a boiler rigidly secured to said frame structure at the front end portion thereof and slidably mounted thereon at 15 the rear of said front end portion to provide for free longitudinal movement of said boiler independently of said frame structure due to expansion and contraction of said boiler; a shroud structure covering said boiler forward of said cab 20 about its top and sides; means rigidly securing said shroud structure to said frame structure; means rigidly securing said cab to said shroud structure; and means for flexibly connecting said cab at the front top portion thereof with said 25 boiler, supporting said cab from said boiler to prevent lateral movement of said cab and said shroud structure adjacent thereto relative to said boiler and to permit said free longitudinal movement of said boiler independently of said cab.
- 30 13. In a locomotive, a main frame having a boiler and a running board at each side thereof; a streamline shroud structure forming an outer covering for the sides and top of said boiler and extending at each side to the running board adjacent thereto, said running boards and shroud structure being supported by said main frame; and a cab having its front wall adjacent the rear edge of said shroud structure and comprising a 35 portion extending laterally beyond said shroud structure at a side thereof with its inner edge adjacent the side of said shroud structure and its bottom edge adjacent the rear edge of the running board adjacent thereto, said cab por-

tion being inclined from its inner edge outwardly and from its bottom edge upwardly in rearward directions.

14. In a locomotive having a main frame and a boiler rigidly secured at one of its ends to said main frame and slidably supported by said main frame beyond said secured end to permit said boiler to expand and contract in a longitudinal direction independently of said main frame, a streamline shroud structure forming an outer covering for the sides and top of said boiler having an opening formed therein and rigidly secured at its lower side edges to said main frame; a sandbox rigidly secured to said boiler opposite said opening having a filling opening formed therein in vertical alignment with said shroud opening; and a collar secured to said shroud structure about said opening formed therein and cooperating with said filling opening in horizontal spaced apart and vertically overlapped relation whereby said sandbox may move with the said boiler longitudinally of said locomotive independently of said collar and shroud structure. 5 10 15 20

16. The combination with a locomotive, of a shroud structure comprising a streamline shroud forming an outer covering for the sides and top of said locomotive, formed of separate plates having adjacent edges disposed in planes transverse of said locomotive, a framework disposed interiorly of said shroud upon which said shroud rests, plate-retaining bands engaging the outer faces of said plates and extending over said adjacent edges, and adjustable means for drawing said bands tightly upon said plates whereby said plates will be securely held in position upon said framework, said framework and bands, with their adjustable means, being supported by said locomotive, said separate plates being entirely free from attachment to each other, to said framework and to said locomotive, leaving each of said plates entirely free for independent removal upon the releasing of its retaining bands. 25 30 35 40

JAMES G. BLUNT.
